CLOTHES RACK

John Huhn, Jr., Detroit, Mich.

Application November 22, 1946, Serial No. 711,594

1 Claim. (Cl. 211—86)

1

The present invention relates to supports and specifically to racks or supports for articles of clothing or other articles after ironing.

Among the objects of the invention is a rack or support readily attachable and detachable from an ironing board but which may be left fixed in place and folded flat with the board so as to permit the latter to be stored.

Another object is to provide a rack or support which is readily erected from its flat position and rotated to prevent interference with the operator.

Still other objects and advantages will be apparent to those skilled in the art upon reference to the following description and the accompanying drawings in which

Figure 1 is a perspective view showing a portion of an ironing board with the support attached and also its use.

Figure 2 is an enlarged view of the support with a part in section.

Figure 3 is a section on line 3—3 of Figure 2.

Figure 4 is a section on line 4—4 of Figure 3.

In the drawing a portion of an ironing board is indicated at 10 with the support means fixed thereto. The support means comprises a C-clamp, indicated as a whole at 11, adapted to embrace an edge of board 10 and fixed thereto by means of a clamp screw 12. The clamp 11 is, on its outer face, provided with a tubular boss 13 extending horizontally and supported by a web 14A. The boss 13 is further provided with horizontally arranged openings 14 in its side walls and carries slidably therein a plug member 15 having an opening 16 adapted to register with the openings 14.

Plug 15 is provided with an axially arranged threaded shaft or screw 17 adapted to extend beyond boss 13 and cooperate with a nut 18 preferably shaped to form a hand operable knob and finished at its inner end to cooperate with and slide smoothly on the end of boss 13.

Into the openings 14 and 16 is inserted the lower end 20 of an upright member 21, the lower end portion being arranged at a right angle to

the upright portion 21, and being fixed against rotation by tightening the nut or knob 18. Near its upper end the upright member 21 is provided with a shallow groove 22, and seated upon this upper end is a cap member 23 provided with a suitable thumb screw 24 adapted to enter the groove 22 to retain the cap against dislocation and permit it to rotate or be fixed at the will of the user.

5 Fixed to cap 23 is a horizontally extending arm 25 adapted to serve as a support for the ironed articles 26.

In use, the operator will rotate the arm 25 to a suitable location and fix its position or not, according to individual preference. When the ironing has been completed and it is desired to store the board 10, the arms 21 and 25 may be folded flat against the board by loosening knob 18.

I claim:

20 A rack for ironed articles consisting of a C-clamp adapted to be fixed to an ironing board, a cylindrical hollow boss on said clamp, a plug slidable therein, said boss and plug being provided with registering openings constituting a 25 passage therethrough, an arm having a portion adapted to enter said passage, said arm normally extending vertically, and having a laterally extending branch, and means for moving relatively said plug and boss whereby to fix said arm portion 30 against movement in said passage.

JOHN HUHN, JR.
